UNITED STATES PATENT OFFICE.

DARNELL A. DANCE, OF CHICAGO, ILLINOIS.

DIRECTORY BOARD.

Application filed April 2, 1923. Serial No. 629,443.

To all whom it may concern:

Be it known that I, DARNELL A. DANCE, a citizen of the United States, and a resident of Chicago, in the county of Cook and 5 State of Illinois, have invented certain new and useful Improvements in Directory Boards, of which the following is a specification.

This invention relates to a directory board 10 for office buildings or the like.

The object of the invention is to provide a board of this character, whereby each tenant in an office building may indicate on 15 the directory board whether or not his office is occupied.

A further object of the invention is that the indicating means be mechanically operated whereby to insure that no mistakes occur.

20 A still further object of the invention is that the directory board including the indicating means be of neat structure and durable.

Other objects and objects relating to 25 details of construction, combination and arrangement of parts will hereinafter appear in the detailed description to follow.

The invention is illustrated by way of example in the accompanying drawings, in 30 which:

Figure 1 is a perspective view of a directory board constructed in accordance with the present invention,

Figure 2 is a view showing in front elevation 35 an upper end portion of a directory board, and also a lower end portion of the directory board, parts of the lower end portion being removed to more clearly illustrate the construction of the directory board,

Figure 3 is a horizontal transverse sectional view of the directory board,

Figure 4 is a detailed perspective view 40 illustrating the manner in which the letters for forming the names may be supported,

Figure 5 is a group view illustrating the operative parts of each signal unit or element, and

Figure 6 is a fragmentary rear elevation 45 of the indicator panel of the directory board and particularly illustrating the manner in which the signal elements are mounted thereon.

Referring to the drawings more particularly, the directory board may comprise a 50 supporting wall 10 which may be formed of boards or the like, and which is enclosed in

a frame, said frame comprising the two side members 11 and the top and bottom members 12 and 13, respectively. It will be noted that the frame members extend from 60 the forward face of the wall 10, and that the top and bottom members 12 and 13 are of greater width than the side members 11. Between the members 12 and 13, there is secured a panel 14 which may be referred to 65 as an indicator panel. A door is hinged to each of the side frame members 11, and each door may comprise a suitable frame including a pair of side members 15, and a pair of end or cross members 16, and each frame 70 being adapted to support a glass panel 17. Each door is hinged to its associated side frame member 11 as at 18, and as shown in Figure 1, upon closing these doors the outer 75 surface of the frames thereof is flush with the outer edges of the frame members 12 and 13 and also flush with the outer surface of the panel 14. By constructing the directory board in this manner it is apparent that a neat and artistic structure is had. 80

Upon each side of the panel 14, there is arranged a plurality of letter supporting strips 19, said strips in each instance being arranged one above the other, and extending in parallel relation. Each strip is secured in position by screws 20. Referring to Figure 4, 21 indicates letters which are preferably of metal and in the formation of each letter there is provided at the upper end thereof one or more tangs 22. At 90 23 there is shown numerals which are likewise formed of metal, and also each numeral is provided with one or more tangs as at 25, for supporting the same. In arranging these letters upon a supporting strip 19 as shown in Figure 1, the tangs 22 are bent so that the same may engage over the upper edge of the associated strip 19 as illustrated to advantage in Figure 4. By arranging the tangs the letters are efficiently supported and also may be easily removed when desired. The numerals 23 may be likewise positioned. 95

As shown in Figure 1, each strip 19 is adapted to support sufficient letters to indicate a name of an office tenant and also support numerals to indicate the room number of this particular office. 105

Adjacent each longitudinal edge of the panel 14 is provided a series of openings 110 26. The openings 26 in each series should correspond in number to the number of

supporting members 19 occurring upon the associated side of the panel 14, and each opening 26 should be in alinement with the associated supporting member 19 as illustrated in Figure 1 of the drawing. For each opening 26 there is provided a signal element 27, and referring to Figures 5 and 6, it will be seen that this signal element comprises a strip preferably of metal, which 10 has printed adjacent one end and upon its inner face with respect to the panel 14, the word "In" and adjacent its other end is printed the word "Out". Each signal element 27 is turnably supported by a stem 30, said stem having its inner end extended through a central opening in the associated signal element 27, and having its outer end formed with a knurled head 31 whereby the same may be manually rotated. As is apparent, by rotation of the stem 30 in each instance, the signal element 27 carried thereby may be disposed so that either the word "In" or "Out" printed thereon is brought into registering relation with the opening 26.

In the use of the present directory board, the same should be mounted in an office building where each of the tenants may have easy access thereto, and also in such 30 a position that the same may be easily observed by those entering the building. The names of the tenants of each of the offices may be arranged upon the board as illustrated in Figure 1, and each tenant may 35 manipulate his own indicating element to show whether or not he is in his office. For the purpose of further illustration, assuming that the office tenant is entering the office building in which this directory board 40 is positioned, and intends to be in his office for a certain time, he should then go to the directory board and manipulate his particular indicator element so that the same would display the word "In". If a per-

son should come to this office building to 45 call upon this particular tenant then he could quickly and easily ascertain whether the tenant was in. In case this same tenant should desire to leave the building for a certain length of time, and close his office, then he should manipulate his indicator element so that it should display the word "Out", and thus notify callers that he is 50 out of his office.

I claim:—

1. A directory board of the character described, comprising a frame, a closure for said frame adapted to form a rear wall therefor, a panel extending longitudinally of the wall and secured between the end members of said frame, a door hinged to each side member of the frame and adapted to form the closure between said frame member and the associated longitudinal edge of the panel, strips arranged upon said wall and upon each side of the panel adapted to support letters whereby different names may be indicated, and indicating means carried by the panel for each strip, whereby the words "In" or "Out" may be 65 displayed for the purpose described.

2. A directory board having a central panel and means on each side of the central panel for supporting vertical columns of names, and indicating means along each edge of the central panel, one indicating means being provided opposite each name, each indicating means comprising a flat strip having indicia thereon, and means for mounting the flat strip on the under face of the central panel for horizontal turning movement, said central panel having an aperture for each indicating device and through which the indicia of the flat strip may be viewed when the strip is turned so that the indicia underlies the aperture.

DARNELL A. DANCE.
